UNITED STATES PATENT OFFICE.

ANTON LIJEWSKI, OF MILWAUKEE, WISCONSIN.

EXPLOSIVE SHELL.

1,163,022.

Specification of Letters Patent.

Patented Dec. 7, 1915.

Application filed April 17, 1915. Serial No. 22,012.

To all whom it may concern:

Be it known that I, ANTON LIJEWSKI, a citizen of the United States, residing at Milwaukee, in the county of Milwaukee and State of Wisconsin, have invented certain new and useful Improvements in Explosive Shells; and I do declare the following to be a full, clear, and exact description of the invention, such as will enable others skilled in the art 10 to which it appertains to make and use the same.

This invention relates to improvements in projectiles and more particularly to explosive bullets or shells.

15 The primary object of the invention is to provide a shell or bullet which is safe for transportation and storage purposes but of highly explosive properties, efficient in service, and constructed to explode after the 20 projectile has penetrated or partially penetrated the object at which it is directed.

Another object of the invention is to provide a projectile of this character equipped with means for destroying the object at 25 which it is directed by tearing it internally after the projectile has penetrated it.

With these and other objects in view, the invention consists of certain novel features of construction, and the combination and 30 arrangement of parts as will be more fully described and claimed.

In the accompanying drawings: Figure 1 represents a side elevation of a projectile constructed in accordance with this invention; Fig. 2 is a longitudinal section thereof; Fig. 3 is an enlarged longitudinal section of the projectile with the cap removed and arranged in juxtaposition ready for assembling, and Fig. 4 is a transverse section 40 taken on the line 4-4 of Fig. 2.

The cartridge contemplated by the present invention comprises a shell or jacket 1 preferably constructed of steel and having an explosive cap 2 rounded at its rear end 45 and provided at its front end with a reduced tubular extension 3 here shown connected with the body portion of the shell by an inclined shoulder 4.

50 Telescopically engaged with the tubular extension 3 is the projectile 5 of the cartridge and which is here shown in the form of a cylindrical casing 6 closed at both ends by disk-like caps or closures 7 and 8 which are held in connected relation by means 55 of rods 9 which pass longitudinally through the casing and are shown having threaded

engagement with the disks 7 and 8, thereby reliably holding them in operative position.

The front plate 8 of the projectile 5 has an exploding cap 10 mounted therein and 60 arranged in front of this cap carrying plate 8 is a longitudinally extending member 11 having a bore 12 in the center thereof to permit the insertion of a pin 13 carried by a soft metal cap 14, said pin being preferably 65 soldered in said cap and here shown provided with a head 15 mounted in the cap and held by the solder therein. The walls of the casing 6 preferably converge toward their free ends and are externally threaded 70 as shown at 16 to receive the threaded cap 14 which when engaged therewith, will cause the free end of its pin 13 to be disposed adjacent to the cap 10 but spaced therefrom a sufficient distance to render the 75 explosive perfectly safe for storing and transportation and which only becomes dangerous when the metal cap forcibly engages some object such as would exert sufficient pressure to force said cap rearwardly a sufficient distance to engage the pin 13 with the exploding cap 10.

The casing 6 of the projectile 5 is filled with an explosive preferably smokeless powder P and has embedded therein a multiplicity of jagged pieces 17 of steel or other hard material.

The steel jacket or casing 1 is also filled with an explosive material preferably smokeless powder as shown at P'. 90

From the above description, it will be obvious that when sufficient force is brought to bear on the exploding cap 2 such as is caused by the firing of a gun, the powder P' in the shell 1 will be exploded and thereby 95 drive out the telescopically engaged projectile 5 mounted in the front end thereof and the tapered capped end of this member on coming into contact with the object toward which it is directed will have said cap sufficiently flattened, owing to its soft formation so as to cause the pin 13 to be driven inwardly against the exploding cap 10 and thereby explode the powder P in the casing 6 of said member 5, it being obvious that 100 the bullet or projectile 5 will at first only penetrate the object toward which it is directed according to the nature of the object and the impact will cause the explosion of the powder P which will force the jagged 105 pieces 17 against the caps 7 and 8 and the shell or casing 6, thereby tearing the latter 110

open and allowing the pieces 17 to penetrate the beforementioned object.

I claim as my invention:

1. An explosive of the class described comprising a tubular casing closed at its opposite ends and filled with an explosive, an exploding cap in one of said closures, a forwardly tapering chamber encircling said cap carrying closure and arranged in longitudinal alinement with said casing, said chamber having its outer end threaded, a soft metal cap having threaded engagement with said chamber, said cap tapering toward its free end and having a pin mounted therein and extending longitudinally rearward with its free end positioned adjacent said explosive cap when the parts are assembled.
- 10 2. An explosive of the class described comprising a tubular casing, a pair of disks closing the opposite ends of said casing, rods secured to said disks for holding them in connected relation, said casing being filled with an explosive having jagged elements embedded therein, an exploding cap in one of said disks, a forwardly tapering chamber arranged in longitudinal alinement with said

casing, the outer end of said chamber being threaded, a soft metal cap having threaded engagement with said chamber, said cap tapering toward its free end and having a pin mounted therein and extending longitudinally rearward with its free end positioned adjacent said explosive cap when the parts are assembled.

3. An explosive of the class described comprising a tubular casing closed at its opposite ends and filled with an explosive, an exploding cap in one of said closures, a forwardly tapered chamber encircling said cap carrying closure and arranged in longitudinal alinement with said casing, said chamber having its outer end threaded, a soft metal cap having threaded engagement with said chamber, said cap tapering toward its free end and having a pin mounted therein and extending longitudinally rearward with its free end positioned adjacent the explosive cap of said closure when the parts are assembled.

In testimony whereof I have hereunto set my hand in presence of two subscribing witnesses.

ANTON LIJEWSKI.
